BOTTLE CRATE

Lloyd Hale, Minneapolis, Minn., assignor to G. H. Tennant Company, Minneapolis, Minn., a corporation of Minnesota

Application March 20, 1931, Serial No. 523,975

12 Claims. (Cl. 217—19)

Heretofore bottle crates have been made in various manners to support the bottles in individual compartments within a casing. The casing usually is formed in a manner so as to permit one case to be stacked upon the other so that in the milk station or creamery when the bottle cases are filled with milk bottles, the bottles will be inverted and washed out right while they are in the case and then turned over in the individual compartments in the case and filled with milk, passing on gravity carriers into the cooling room and then carried out into the districts to deliver the same to the different homes. This calls for a crate structure which will withstand certain handling conditions and accomplish the desired results in a simple manner. It is important that these crates be made economically, easy to assemble, and readily repaired if it is necessary.

I have provided a crate wherein the sides are preferably made of non-metallic strips or slats and where the corners are reinforced by metal angle members extending over the inside and outside of the corners, which members are secured together to hold the slats forming the side walls in place.

The novel features of my crate reside in the partition members which are made of strips of metal having the sides bent down to provide an arcuate portion in the flat strip with slightly depending arcuated flanges formed by the bending down of the sides of the strip. These strips intersect and are secured together at their intersecting points by stay-rivets of my peculiar construction which extend from one partition to the other.

The partitions are superimposed directly above each other and the stay-rivets extend between the two partitions to hold the same equally spaced apart and to reinforce the thin flat strips which form the dividers of the partitions to divide the inside of the bottle crate into individual bottle compartments. Were it not for the stay bolts the thin flat strips would not be strong enough to withstand the wear and handling to which a bottle crate is subjected.

The partition of this crate is formed with two unit-like portions secured together to provide a complete partition unit, that is, one set of strips which act as dividers are placed intersecting each other at right-angles and are positioned above the other similar set and then these two sets are secured together by the stay-rivets.

When the partition is in this form as a unit, it is positioned in the bottle crate in the making of

the same and the other slat members which form the side walls are secured above so as to hold the partition anchored in the slatted side walls. The stay-bolts perform an important function in strengthening and properly spacing the partition sections apart so as to provide a complete unit. These stay-bolt rivets also provide the securing means for holding the spacers of the sections of the partition riveted together at their intersecting points. A peculiar formation of stay-bolt is used to accomplish the desired results.

The drawing illustrates in Figure 1 a perspective view of my milk crate.

Figure 2 illustrates a section of the milk crate, 15 across the narrow dimension thereof.

Figure 3 illustrates a similar section to Figure 2, across the long or longitudinal dimension of the crate.

Figure 4 illustrates one end of the stay bolt 20 rivets as it would appear in being set in the strips which form the spacers, the strips being illustrated in section.

Figure 5 is a similar view to Figure 4, showing a portion of the rivet-bolt after it has been 25 set and riveted in place, and showing the spacers in section.

Figure 6 illustrates a spot welded brace structure between the sets of spacers.

In the drawing the crate A is formed of wooden slats 10 which may be narrow strips of wood or other non-metallic members. These strips 10 are placed edge to edge superimposed to form the side walls of the crate A.

The bottom slats 11 are reinforced with a 35 metal channel-shaped member 12 to provide a strong wearing surface for the bottom of the crate A. This is important because the crate in being carried over gravity carriers would be all chewed up along the bottom by the wear and 40 tear on the same, were it not for the reinforced edge 12 on the bottom slats 11.

The case A is divided into individual bottle compartments such as B by the partition unit C which is made up of a series of intersecting 45 flat strips 14 and 15. These strips intersect each other at right-angles and are formed with arcuated portions 16 which provide the downward extending arcuated flange 17 in each compartment on the sides of the strips 14 and 15. 50 The strips 14 and 15 are of thin metal and the arcuated flanges 17 provide bottle engaging faces in the compartments B.

To hold the unit C assembled with the strips 14 and 15 extending as spacers in sets such as 55

C1 and C2, I provide spacer rivet-bolts or rods 18 which not only act as spacers at each intersecting point of the strips 14 and 15, but are also reinforcing stay-bolts which space the sections C1 5 and C2 apart and hold them together as an entire unit C which forms the partition unit of the crate A.

The stay-bolts or rods 18 are formed in a peculiar manner with a rod portion on the ends 10 of which an annular flange 19 is formed, together with a tapered riveting end 20. By reason of this tapered end when the same is placed in the openings 21 in the members 14 and 15 and drawn up tight to rivet over a head like 22 in Figure 5, a 15 water and moisture-tight joint is provided between the shoulder 19 and the head 22. At the same time, the strips 14 and 15 are held riveted together at their intersecting points.

A flat thin spacing plate of sheet metal 23 20 extends between the sides of the crate A as illustrated in Figure 2 and also illustrated in Figure 3 in cross-section. This plate is secured at 24 to the side walls, while pairs of rods 25 extend through the same near the lower edge thereof. 25 These rods 25 form the bottoms for the compartments B and the bottles rest directly upon the rods 25 either in upright or inverted position. Brace rods 26 extend transversely across the crate and over these rods I provide a channel brace 27. The longitudinal bottom rods 25 extend through the channel 27 and the transverse brace rods 26 support the channels between the side walls. The spacer plate 23 engages under the center cross strip of the partition unit C as 30 illustrated in Figure 3. This spaces the center of the unit C from the bottom rods 25 and acts to support and brace the center of the unit C in the 35 crate A.

The unit partition C is formed with its ends 40 adapted to extend between the abutting faces of the slat members 10, as illustrated in Figures 2 and 3, and suitable anchoring pins 28 are adapted to hold the ends of the partition in anchored position in relation to the side walls of the case A.

The simplicity of structure of this crate 45 accomplishes a desired result in forming a partition unit C by the stay-rivets or bolts 18 and the intersecting flat strips 14 and 15 which have arcuated flanges formed therein. These parts are 50 held together in a unit and placed in the crate A and form a means of partitioning the same into individual bottle compartments B. The reinforcing plate 23 acts to support the center of the unit C which rests upon the plate 23 and co-operating with the braces and bottom rods 25, reinforces and properly spaces the parts of the crate A, holding the center portion C of the partition 55 from sagging as well as assisting to support the rods 25. This brace plate extending transversely 60 in the bottom of the case A forms a sheet-like brace through the center of the same.

The side slats 10 when in place, anchor the 65 ends of the partition unit C, and the outside corner angles 30 cooperate with the inside corner angles 31 to hold the ends of the slats 10 rigidly together by means of the rivets 32 which extend through the corner members 30 and 31 and the slats 10 to rigidly connect the same and reinforce the case at the corners. The unitary partition C 70 with the upper and lower sections all connected together by the stay-rivets 18 permit easy assembly of the parts and when the case A is all together a very strong and substantial structure is provided in an economical manner.

75 I have described and set forth in accordance

with the patent statutes the principles of the invention with the novel features thereof, and the same should be interpreted within the scope of the following claims.

I claim:

1. A bottle crate including, a unitary partition having upper and lower sections, rivets for holding said sections together, and a sheet-like brace member extending across within said crate to brace the center portion of said partition unit. 10

2. A bottle crate comprising side and end walls, a sheet-like brace plate extending between said side walls, and a unitary partition formed of a series of strips held together at right angles to each other in sections, one section being superposed to the other, brace rivets extending between said sections, said brace plate in said crate acting to support the center portion of said partition unit. 15

3. A bottle crate including, side and end walls, 20 pairs of rods extending longitudinally along the bottom of said crate to form a rest for the bottles in the crate, channel-shaped supporting members extending transversely between the sides of said crate, rods in the tops of said channels for 25 supporting the same, said pairs of rods extending through said channels below the supporting rods for said channels, a center brace plate through which said pairs of rods extend positioned between the sides of said crate, a unitary 30 partition formed of superimposed sections, rivet spacer rods holding said sections spaced apart, said brace plate supporting said unitary partition centrally, and means for anchoring the ends of said unitary partition to the walls of said 35 crate.

4. A crate partition connecting means for connecting superimposed crate partitions including, a rod, shoulders spaced from the ends of said rod for bearing against said partition units to 40 properly space the same, and a rivet head on either end of said rod whereby said rod may be secured rigidly to the partitions.

5. A crate partition connector for connecting superimposed crate partitions including, a rod, 45 shoulders on said rod spaced from the ends thereof adapted to engage against a pair of superimposed partitions, and a tapered rivet end on said connector extendable through said partitions, whereby said partitions may be secured together 50 by riveting said tapered ends.

6. A bottle crate including a unitary partition having upper and lower sections each formed of intersecting flat strips, said strips positioned with one flat surface uppermost, vertical spacer rivets 55 adapted to extending through the intersecting points of said strips of both sections and secure said sections together, means on said rivets to space said strips apart, and means for anchoring said unit in the side walls of said crate. 60

7. A partition unit for bottle crates including, sections each made of flat strips laid one upon the other with one flat surface uppermost, and intersecting at right angles, and vertical stay-rivets extending through said strips to secure said 65 strips together at their intersecting points with a moisture-tight joint, and shoulder means on said rivets to space said strips of different sections.

8. A partition unit for bottle crates including, 70 upper and lower sections, each comprising flat strips with one flat surface uppermost and intersecting at right angles, vertical stay-rivets extending through said strips of both sections to secure said sections together, and ends formed 75

on said strips for anchoring said unit in a bottle crate.

9. A partition unit for bottle crates comprising, upper and lower sections each including flat strips intersecting at right angles, and stay brace means extending through the strips of said sections including means to space the strips of different sections apart and form a reinforcing brace between the same.

10 10. A bottle crate including, a number of superimposed partitions spaced one above another, and a brace connected to the lowermost partition of said number, said brace extending into contact with, but not connected to, the partition next adjacent the said lowermost partition.

11. A bottle crate including, a number of superimposed partition members spaced one above

the other, a brace connected to the lowermost member of said number upon which the next adjacent partition above said lowermost partition rests but is not connected, and means for connecting the partitions above said lowermost partition rigidly together.

12. A crate partition structure including a pair of spaced flat partition members, and means for connecting said partition members including a rod, shoulder means spaced from each end of said rod, each shoulder means contacting one of said pair of spaced partition members to hold the members in spaced relation, and ends on said rod holding said spaced partition members against said shoulders.

LLOYD HALE.
